United States Patent Office.

PETER H. MELLON, OF ST. LOUIS, MISSOURI.

Letters Patent No. 78,989, dated June 16, 1868.

IMPROVED QUILTING-FRAME.

The Schedule referred to in these Letters Patent and making part of the same.

TO ALL WHOM IT MAY CONCERN:

Be it known that I, PETER H. MELLON, of St. Louis, in the county of St. Louis, and State of Missouri, have invented a new and useful Improvement in Quilting-Frames; and I do hereby declare that the following is a full, clear, and exact description thereof, which will enable others skilled in the art to make and use the same, reference being had to the accompanying drawings, forming part of this specification, in which—

Figure 1 is a top view of my improved quilting-frame.

Figure 2 is a vertical section of the same, taken through the line $z z$, fig. 1.

Similar letters of reference indicate corresponding parts.

My invention has for its object to so improve the construction of quilting-frames as to make them more convenient in use, enabling the quilt to be shifted, and the frame taken apart and put together, or adjusted at any desired height, quickly and conveniently; and it consists in the construction and combination of the various parts, as hereinafter more fully described.

A are the stands which support the frame, and which are formed by removably attaching the lower ends of the uprights a^1 to the base-blocks a^2 .

The base-blocks a^2 should be made sufficiently large and heavy to securely ballast the frame. The uprights a^1 may be attached to the blocks a^2 by having tenons formed upon their lower ends, entering holes formed in the said blocks; or, if desired, the tenons may be made round, and may have screw-threads cut upon them, so as to screw into the said blocks.

B are the side-bars of the frame, the outer sides of which are grooved transversely, to fit upon the uprights a^1 of the stands A, to which the said side-bars are secured by hand-screws C, which pass through holes in the said uprights a^1 , and screw into holes in the centres of the said bars B.

Several holes are made in the uprights a^1 , for the reception of the screws C, so that the frame may be adjusted at any convenient or desired height.

D are metallic plates, attached to the inner sides of the ends of the bars B, and which are slotted, to receive the heads of the journals of the rollers E, one end of said slots being made large, to receive the heads of said journals, and the other ends being made smaller, so that the said heads cannot pass through them.

F are sliding keys, which pass down in grooves between the plates D and the bars B, so as to cover the enlarged parts of the slots through said plates, to guard against the journals of the rollers E being able to work themselves out. The movements of the keys F are guided and limited by pins passing through slots in said keys, as shown in figs. 1 and 2.

E are the rollers, to which the article to be quilted is secured in the usual manner, that is to say, by having its edges sewed to strips of cloth tacked or otherwise secured to said rollers.

To the ends of the rollers E are attached disks G, of a larger diameter than said rollers, so as to guard against any part of the article being quilted working off the ends of the said rollers, and becoming entangled with their journals.

Ratchet-teeth H may be formed upon the wheels G, at one or both ends of the rollers E, upon which the pawls I take hold, to hold the said rollers securely in place, the ratchet-wheels and pawls being in reversed positions upon the two rollers, as shown in fig. 1.

J is a bar, which may be passed through holes in the roller E, for convenience in revolving it.

Having thus described my invention, what I claim as new, and desire to secure by Letters Patent, is—

Securing the rollers E in the ends of the bars B, by means of the slotted metallic plates D and slotted sliding plates F, as herein shown and described.
